United States Patent Office

Des. 227,318
Patented June 19, 1973

227,318

HAT

Charles P. Martyn, R.R. 1, Hutchinson Island,
Stuart, Fla. 33494

Filed June 16, 1970, Ser. No. 23,515

Term of patent 14 years

Int. Cl. D2—03

U.S. Cl. D2—247

Fig. 1

Fig. 2

FIG. 3

FIG. 4

FIG. 1 is a side perspective view of a hat showing my new design;

FIG. 2 is an enlarged top plan view thereof with the straps in an unfastened position, the side opposite being substantially plain;

FIG. 3 is a side elevational view with the straps shown broken away for convenience of illustration; and

FIG. 4 is a front elevational view of a second embodiment of the design shown in FIG. 1.

I claim:

The ornamental design for a hat, substantially as shown and described.
